LOOM SHUTTLE

John J. Kaufmann, Jr., Greenville, S. C., assignor
to Steel Heddle Manufacturing Company,
Philadelphia, Pa., a corporation of Pennsylvania

Application January 11, 1945, Serial No. 572,358

7 Claims. (Cl. 139—217)

1

This invention relates to shuttles for looms, and it relates more particularly to the provision of improved means, in such shuttles, for maintaining the proper tension on the filling yarn as the shuttle is passed back and forth through successive sheds of the warp.

In the shuttles which are used in the modern types of automatic looms a threading block is usually provided at one end of the shuttle, which block is provided with means for automatically causing the filling yarn to be threaded in the shuttle immediately after the bobbin has been replenished in the shuttle. Such threading blocks are made in various shapes and styles and in some instances, where it is desirable to control the tension of the filling thread more or less accurately, said threading blocks are provided, usually at the end thereof to which the filling thread is fed from the bobbin to the threading block, with spring pressed members between which the thread travels as it passes to the channel of the threading block, and thereby there is provided a uniform tension on the filling yarn as the shuttle passes from side to side of the loom in the operation thereof.

Various forms of such tension devices have heretofore been suggested, and it has long been recognized, as a desideratum, to provide, in connection with the tension members, some means, or an arrangement thereof, whereby there will be a tendency of the filling yarn to pass downwardly at the entrance end of the threading block, to the end that there will be less likelihood of the shuttle becoming unthreaded during the operation of the loom, by reason of overthrows or loops which sometimes occur upon the reversal of movement of the shuttle. However, such devices or arrangements have not proved entirely satisfactory in use.

The principal object therefore, of the present invention, is to provide an improved form of tension device for automatically threading shuttles, which is so constructed and arranged as to cause the filling yarn to pass downwardly into the lower portion of the thread channel and to so maintain said yarn so that likelihood of unthreading of the shuttles from overthrows or loops will be greatly minimized.

A further object of the invention is to provide a tension device, of the character aforesaid, in which the initial threading of the shuttle will be greatly facilitated by reason of the ease with which the filling thread will pass to the proper location between the tension members.

A further object of the invention is to provide

2 a tension device, of the character aforesaid, which will be simple and inexpensive in construction, which may be readily and easily assembled in the threading block, and which is adjustable therein without dismantling the same.

5 The nature and characteristic features of the invention will be more readily understood from the following description, taken in connection with the accompanying drawing forming part 10 hereof, in which:

15 Figure 1 is a top or plan view of the threading end portion of a loom shuttle having a threading block mounted therein and provided with a tension device embodying the main features of the 20 present invention;

Fig. 2 is an enlarged end elevation of the threading block detached from the shuttle, illustrating more particularly the construction and arrangement of the tension members which are 25 mounted therein;

Fig. 3 is an enlarged longitudinal section of the 30 threading block detached, the section being taken on the line 3—3 of Fig. 2;

Fig. 4 is an enlarged horizontal section of a 35 portion of the threading block, taken on the line 4—4 of Fig. 2;

Fig. 5 is an enlarged horizontal section of a 40 portion of the threading block, taken on the line 5—5 of Fig. 2; and

Fig. 6 is an enlarged longitudinal section of a 45 portion of the threading block as shown in Fig. 3, but illustrating a modified form of tension member.

It should, of course, be understood that the 50 description and drawing herein are illustrative merely, and that various modifications and changes may be made in the structure disclosed without departing from the spirit of the invention.

Referring to the drawing, in the particular 55 embodiment of the invention therein shown, the shuttle body 10 is preferably made of wood, and has the usual bobbin chamber 11 in which the bobbin 12 is held by the usual gripping means (not shown), whereby it may be readily discharged therefrom and a new bobbin substituted as the filling runs out from time to time.

The shuttle body 10 is also provided with the 60 usual side delivery eye 13 for the passage of the filling yarn 14. The threading block 15 comprises primarily a casting preferably made of metal, either cast iron or brass as desired. Said block 65 15 has its outer side surfaces 16 and 17 preferably parallel with each other, and its bottom surface 18 substantially at right angles thereto. The

body portion of the threading block 15 is fitted into a complementally shaped groove 19 in one end of the body portion 10 of the shuttle.

The body portion of the threading block 15 is provided with a longitudinal channel 20 through which the filling thread 14 passes to the side delivery eye 13 during the weaving operation and as said filling yarn is laid in the cloth.

The threading block 15 may also be provided with a rearwardly extending horn portion 24, and an intermediate horn portion 25 extending into the longitudinal channel 20 of the threading block 15, said horn portion 25 serving to assist in the initial threading of the block, and in the retention of the filling yarn therein after the threading operation has been completed.

At the inner end of the threading block 15, that is, the end disposed toward the bobbin, there is mounted a pair of tension members 26. The inner end of the threading block 17 is recessed vertically, as at 28, for the mounting of said tension members 26 therein.

The lower ends of the tension members are each provided with a suitable aperture 29 through which extends a pin 30 mounted in the lower portion in the inner end of the threading block 15. The upper end of each of the tension members is bent over as at 31 to provide lug like extensions 32 which are positioned respectively in suitable apertures 33 provided in the inner end of the threading block 15. In this manner the tension members 26 are guided at both the top and the bottom.

For the purpose of imparting the required tension to the members 26 so that the same will grip the filling yarn and function in the desired manner as hereinafter set forth, there are provided coil springs 34 which are positioned in the inner ends of the hollow screws 35. The hollow screws 35 are threaded in the side walls of the threading block 15 in alignment with the pin 30 at the bottom and the guiding apertures 32 at the top. The hollow screws 35 thus serve to provide means for regulating the degree of tension on the members 26.

The co-acting faces of the tension members 26 are preferably made flat, as has been the practice heretofore, but in the present instance said co-acting faces of the tension members are tapered toward the bottom for a purpose to be presently explained. The tension members may, of course, be provided with the usual side flanges 40 at either the entrance side or on the other side thereof as at 41. The essential requirement in connection with the present invention is that the co-acting faces of the tension members be tapered toward the bottom.

Preferably the flanges 40 at the entrance side overlap the sides of the slot 28, in which the tension members 26 are positioned, and extend into recesses 43 in the inner end face of the threading block. Also the flanges 40 are preferably disposed parallel to the vertical axis of the tension members and are connected to the main face portions thereof by inclined and reversely tapered portions 44.

It should also be noted that the flanges 40 along the entrance sides of the tension members 26 are disposed at a somewhat greater distance from the vertical plane which passes through the axes of the coil springs than are the flanges 41 along the opposite sides of said tension members. In this manner the pressure exerted along the edge at which the filling thread enters the threading block will be considerably less than along

the other edge thereof. This arrangement will tend to facilitate the passing of the filling thread to the proper location between the tension members when the threading action takes place. This arrangement will also serve to increase the efficiency of the tension device and reduce the likelihood of breakage of the filling thread from knots or unevenness therein.

In the modified form of the invention shown in Fig. 6 of the drawing the face portion of the tension member 26a is tapered from the top to the bottom by providing an inclination along each of the side edges thereof, and in this manner the degree of the taper may be increased. In this instance the flange 41a will also be reversely tapered.

In either of the foregoing arrangements the filling yarn, as it travels between the tension members, will be caused to pass downwardly by reason of its natural inclination to take the path of least resistance and to position itself where the width of the tension members is less. Furthermore, the reverse taper of the portions 44 will assist in causing the filling thread to be impelled downwardly as it runs through the threading block.

I claim:

1. In a loom shuttle of the automatic threading type a tension device comprising a pair of spring pressed tension members between which the filling yarn passes, said tension members having flat coating faces tapered from the top toward the bottom.

2. In a loom shuttle of the automatic threading type having a threading block mounted in one end thereof which threading block is provided with a longitudinal thread channel through which the filling yarn passes from the bobbin to the outlet and spring pressed tension members mounted in the threading block between which the filling yarn passes, said tension members having their coating faces tapered from the top toward the bottom and having reversely tapered portions along their entrance sides.

3. In a loom shuttle of the automatic threading type having a threading block mounted in one end thereof which threading block is provided with a longitudinal thread channel through which the filling yarn passes from the bobbin to the outlet and spring pressed tension members mounted in the threading block between which the filling yarn passes, said tension members having their coating faces tapered from the top toward the bottom and having flanges along their entrance sides connected to the face portions by reversely tapered portions.

4. In a loom shuttle of the automatic threading type having having a threading block mounted in one end thereof which threading block is provided with a longitudinal thread channel through which the filling yarn passes from the bobbin to the outlet and spring pressed tension members mounted in the threading block between which the filling yarn passes, said tension members having their coating faces tapered from the top toward the bottom and having flanges along their sides.

5. In a loom shuttle of the automatic threading type having a threading block mounted in one end thereof, which threading block is provided with a longitudinal thread channel through which the filling yarn passes from the bobbin to the outlet, and spring pressed tension members mounted in the threading block between which the filling yarn passes, said tension members hav-

ing flat coacting faces tapered from the top toward the bottom.

6. In a loom shuttle of the automatic threading type having a threading block mounted in one end thereof, which threading block is provided with a longitudinal thread channel through which the filling yarn passes from the bobbin to the outlet, and spring pressed tension members mounted in the threading block between which the filling yarn passes, said tension members having their coacting faces tapered from the top toward the bottom and having the edges along the entrance sides thereof disposed a greater distance from the point of application of the spring pressure than the edges along the opposite sides thereof. 15

7. In a loom shuttle of the automatic threading type having a threading block mounted in one end thereof, which threading block is provided with a longitudinal thread channel through which the filling yarn passes from the bobbin to the outlet, and spring pressed tension members mounted in the threading block between which the filling yarn passes, said tension members having their coacting faces tapered from the top toward the bottom and having flanges along the sides, the flanges along the entrance sides being disposed a greater distance from the point of application of the spring pressure than the flanges along the other side.
